(57) **CLAIM**

The ornamental design for a transmitter housing, as shown and described.

DESCRIPTION

FIG. 1 is a front perspective view of the transmitter housing in accordance with an embodiment;
FIG. 2 is a front elevational view thereof;
FIG. 3 is a rear elevational view thereof;
FIG. 4 is a first side elevational view thereof;
FIG. 5 is a second side elevational view thereof;
FIG. 6 is a top plan view thereof;
FIG. 7 is a bottom plan view thereof; and,
FIG. 8 is a rear perspective view thereof;
The broken lines in the drawings illustrate the portions of the design that form no part of the claim.
